CLAIM

The ornamental design for a shower assembly, as shown and described.

DESCRIPTION

FIG. 1 is a perspective view of the shower assembly

FIG. 2 is a front elevation view of FIG. 1;

FIG. 3 is a rear elevation view of FIG. 1;

FIG. 4 is a right side view of FIG. 1;

FIG. 5 is a left side view of FIG. 1;

FIG. 6 is a top plan view of FIG. 1; and,

FIG. 7 is a bottom plan view of FIG. 1.

The broken lines in the Figures are presented for the purpose of illustrating environment and form no part of the claimed design.

1 Claim, 5 Drawing Sheets
